G. F. LYBECK

INTERNAL COMBUSTION ENGINE

Filed June 3, 1925

Inventor:

Gunnar Fredrik Lybeck,
By *Neumann* atty

UNITED STATES PATENT OFFICE.

GUNNAR FREDRIK LYBECK, OF AUGUSTENDAL, NEAR STOCKHOLM, SWEDEN.

INTERNAL-COMBUSTION ENGINE.

Application filed June 3, 1925, Serial No. 34,660, and in Sweden June 26, 1924.

In internal combustion engines working without injection of water it is desirable to adjust the temperature of the combustion chamber to maintain said chamber sufficiently hot at no-load and low load so as to enable the fuel to ignite without failure, but prevent the fuel from being superheated at higher loads. To this end it has been proposed to provide the combustion chamber with a cooling jacket having controlling means to permit starting or shutting off the circulation of the cooling liquid.

If water containing salt or lime is used as circulating liquid within said jacket, incrusts will be formed upon the inner surface of the jacket which will considerably reduce the heat transfer to the cooling water and may cause a complete obstruction of the cooling channel.

The object of the present invention is to provide simple and easily controlled means to control the flow of the cooling water, at the same time completely avoiding the formation of incrusts on the cooling jacket surface.

One feature of the invention involves the provision of a draining device at or near the lowermost point of the cooling jacket, said draining device being either mechanically controlled or automatically operating in such a way as to be opened or open when the circulation through the cooling jacket is shut off by closing the means through which the jacket communicates with the circulating system so that the jacket will form a completely closed chamber. When thus closing the cooling jacket, while the engine is running or hot, steam will be generated within the closed cooling jacket and will immediately cause the cooling medium to discharge through the draining device.

In the accompanying, forming part of this specification, one embodiment of the invention is illustrated. Fig. 1 is a vertical section of the combustion chamber of an internal combustion engine having a cooling jacket and controlling means according to this invention, said means being shown in closed position. Fig. 2 is a horizontal section of said combustion chamber and said controlling means. Figs. 3 and 4 are vertical and horizontal sections, respectively, of the

controlling means, shown in completely open position.

With reference to the drawing, the numeral 1 designates the cylinder of the engine with its cooling jacket 2. 3 is the piston reciprocating in the cylinder 1. The cylinder cover 4 is provided with a cooling jacket communicating with the cylinder cooling jacket 2, and carried by the cylinder cover 4 is the combustion chamber 5 closed at its top by a top piece 6 having a fuel injection nozzle 7. The combustion chamber is dimensioned so as to maintain itself sufficiently hot under normal conditions to positively cause ignition of the fuel injected when the engine is running at no-load or at low load, while at the same time avoiding superheating.

To avoid superheating at higher loads the combustion chamber is provided with a cooling jacket 8. The inlet 9 of said cooling jacket is situated near the outlet 10 (Figs. 2, 4) from which it is separated merely by a partition 11. The inlet 9 and the outlet 10 communicate with the interior of a valve casing 12 at either side of a baffle 13 forming an extension of the partition wall 11, said baffle 13 dividing the valve casing 12 into two separate passages 14, 15 in front of a valve 16 serving as a common means to control the connection between said two passages 14, 15 and a supply pipe 17 leading from the cooling jacket of the cylinder cover or between said two passages and a discharge pipe 18 leading to a cooling jacket formed in the top piece 6 of the combustion chamber. The valve 16 is formed with a fork-shaped extension 19 embracing the baffle 13 to form a tight closure between the passages 14, 15 in all valve positions.

The cooling jacket 8 is provided at its top with an air branch controlled by a cock 20.

Extending from a point at or near the bottom of the cooling jacket 8 is a draining passage 21 which is shown as provided with a manually controlled drain cock 22, which may be replaced, however, by an automatic valve designed to open at a predetermined pressure above atmospheric inside the draining passage or cooling jacket.

The valve 16 is controlled by means of a

hand-wheel 23 attached to the valve stem. Said hand-wheel is formed with an inwardly extending, tubular extension 24 adapted to engage a projection 25 formed on the 5 cock 22 (Fig. 3) in such a way as to prevent closing of valve 16 except when the cock 22 is opened. Fig. 3 shows the cock 22 in closed state thereby preventing closing of the valve 16, while in Fig. 1 the cock 22 is shown in open state and the valve 16 in closed state. On the other hand, the cock 22 cannot be closed except when the valve 16 is opened.

The detailed operation of the mechanism 15 is as follows:

At no-load or at low load the valve 16 is maintained in closed position. The cooling water from the cooling jacket 2 of the cylinder 1 or from the cooling jacket of the cylinder cover will now pass behind the valve 16, 20 as indicated in Fig. 2, directly from conduit 17 to conduit 18 and through the latter into the cylinder cover cooling jacket. The cooling jacket 8 of the combustion chamber will, 25 consequently, not receive any cooling water.

If the load on the engine is increased to such a degree as to require cooling of the combustion chamber the valve 16 is opened to allow the water from conduit 17 to enter the cooling jacket 8 by way of passage 14 and opening 9 and, after having passed 30 said jacket 8, to flow out through opening 10 and passage 15 and enter the conduit 18 to then enter the cooling jacket of the top 35 piece 6. The cooling effect thus obtained permits the engine to be overloaded to its utmost degree without any tendency for the engine of being heated too highly. The cooling of the combustion chamber should not be started until after this is required by the 40 load of the engine because, otherwise, misfires may take place as a result of too low temperatures.

The valve 16 may, if desired, also take a 45 half-opened position (not shown) allowing part only of the water from the conduit 17 to pass through the cooling jacket 8, the remaining part of the water passing behind the valve 16 directly into the conduit 18.

Different oils require a different cooling 50 effect and it is, therefore, impracticable to predetermine any load at which the controlling valve should be opened or closed, but experience will settle this after the engine 55 has been running a short time.

In order to prevent to the highest degree 60 possible the formation of crusts upon the inner surface of the cooling jacket 8 the latter should be emptied subsequent to each operation thereof. According to the invention 65 this result is obtained by a rapid and efficient scavenging operation realized by merely closing the controlling valve 16 prior to the stoppage of the engine or, at any rate, 70 while the engine is still hot. Before the

valve 16 can be closed the drain cock 22 should first be opened. The cooling jacket 8 will thus be completely closed except for the cock 22. The steam produced within the cooling jacket 8 due to the heat will now 70 collect over the water surface within the cooling jacket 8 and compel the water to discharge through the drain passage 21 thereby effecting a rapid and thorough draining or 75 scavenging of the cooling jacket. Boiling resulting in the formation of crusts will, thus, be prevented. With the drain cock 22 replaced by an automatic valve the operation will be the same as that above described inasmuch as said valve will open at a certain 80 increase of pressure within the cooling jacket 8.

To start the scavenging or draining process the operator must only close the valve 16, that is, shut off the circulation of cooling 85 water through jacket 8.

Only in case the engine is in cold state the drain cock 20 also should be opened.

A reason in addition to that already stated for training the cooling jacket in connection with the shutting off of the water circulation therethrough is that the starting period of the engine will be short at emptied 90 cooling jacket as compared with that at 95 filled jacket.

What I claim is:

1. In an internal combustion engine, a combustion chamber, a cooling jacket surrounding said chamber, means to circulate water through said cooling jacket and to 100 shut off circulation of water therethrough, a separate draining device communicating with said cooling jacket at a low point thereof, means to control said draining device, said first-mentioned means and said 105 last-mentioned means being designed to mutually control each other, so that the draining device must be open, before the circulation of water can be shut off, and vice versa.

2. In an internal combustion engine, a combustion chamber, a cooling jacket surrounding said chamber, a cooling liquid system, a valve mechanism to connect said jacket in series into said system or disconnect it 115 therefrom wholly or partially, a draining device communicating with said cooling jacket at a low point thereof, connections between said valve mechanism and said draining device to cause said mechanism and said device to mutually control each other in such a way that the draining device must be opened before the valve mechanism can be set to disconnect said cooling jacket from 120 said cooling system.

3. In an internal combustion engine a combustion chamber, a cooling jacket surrounding said chamber, a cooling liquid system, a valve mechanism to connect said jacket in series into said system or disconnect 125 130

nect it therefrom wholly or partially, a
draining device communicating with said
cooling jacket at a low point thereof, con-
nections between said valve mechanism and
5 said draining device to cause said mechanism
and said device to mutually control each
other in such a way that the draining de-
vice must be opened before the valve mecha-
nism can be set to disconnect said cooling
jacket from said cooling system, and an ¹⁰
air escape cock in communication with said
cooling jacket.

In testimony whereof I have signed my
name.

GUNNAR FREDRIK LYBECK.
